Inventor:
 Charles B. Fairchild,
 By W. W. Maldo,
 Atty.

UNITED STATES PATENT OFFICE.

CHARLES B. FAIRCHILD, OF NEW YORK, N. Y.

TAG.

SPECIFICATION forming part of Letters Patent No. 703,698, dated July 1, 1902.

Application filed September 16, 1901. Serial No. 75,468. (No model.)

To all whom it may concern:

Be it known that I, CHARLES B. FAIRCHILD, a citizen of the United States, and a resident of New York city, in the county of New York and State of New York, have invented a Tag or Check, of which the following is a specification.

This invention relates to tags, and relates particularly to tags adapted for use by rail-
road-conductors for identification purposes, in stores for marking goods, and for other similar purposes.

Primary objects of the invention are to provide a tag which may be quickly and conveniently attached to a fabric, as the covering of a car-seat, dry goods, clothing, &c., to provide a tag adapted to be printed or written on and from which pencil-writing may be erased, and to provide a tag which is durable and may be used a great many times.

To this end a tag of my invention consists of the various features, combinations of features, and details of construction hereinafter described and claimed.

In the accompanying drawings a tag of my invention is fully illustrated.

Figure 1 is a front or face view of a tag of my invention, showing in diagram a strengthening-wire. Fig. 2 is a longitudinal sectional view thereof on the line 2-2 of Fig. 1. Fig. 3 is a transverse sectional view thereof on the line 3-3 of Fig. 1. Fig. 4 shows the combined attaching-needle and strengthening-wire removed from the tag. Fig. 5 is a view similar to Fig. 2 of a tag or check embodying my invention in a slightly-modified form; and Fig. 6 is a view of the edge of the tag, showing said tag bent so as to expose the point of the attaching-needle.

Broadly stated, a tag of my invention consists of a ticket or card A of desired shape and size which is flexible and preferably resilient and which may be printed or written upon and from which, preferably, pencil-marks may be erased. Said card or ticket A is provided with a slot a, and extending longitudinally of said slot a is a needle a', which is secured in or to said card or ticket A at one end and the other end of which is free. Thus when the card or ticket A is straight the needle-point will be disposed inside of the lateral surfaces of said card or ticket;

but when said card or ticket is bent, as shown in Fig. 6, said needle a' will be outside of said tag, the point thereof being exposed to admit of sticking it into any fabric to which it is desired to attach said tag.

In its preferable form a tag of my invention consists of two pieces a² of heavy paper, as Manila paper or the like, securely pasted or gummed together.

The slot a preferably extends longitudinally of the tag and is preferably formed adjacent to one end thereof, which may be called the "top," leaving the opposite end or bottom of said tag continuous, so that it may conveniently be written upon.

The needle a' is secured to the tag A at the upper end of the slot a and is practically of the same length as said slot. In the preferable construction shown also said needle a' is formed integral with a spring-wire secured between the layers a² of the tag A, said wire comprising a section a³, which extends practically the entire length of said tag, preferably adjacent to one edge thereof, a section a⁴, which extends across the top of the tag, and a bent section a⁵, which connects the section a⁴ with the upper end of the needle a'. The section a³ of said wire imparts strength and resiliency to the tag, and as a whole said wire strengthens said tag, keeps it straight, and affords convenient means for securely attaching the needle a' thereto. In the preferable construction shown also the tag is thicker at the lower end of the slot a—that is, opposite the end of the needle a'—than elsewhere, thus affording better protection for the point of said needle and preventing the same from being exposed by slight bending of the tag A in handling or from other cause. As shown, the thickness of said tag is thus increased by inserting a piece of pasteboard or other suitable material of desired size and thickness—say one-quarter of an inch square by one-eighth of an inch in thickness—between the layers a² of said tag. In the preferable construction shown also pieces a⁶, of cheese-cloth, muslin, or the like, are secured between the layers a² of said tag, one on each side of the wire therein. Said pieces a⁶ will

decrease the liability of the tag to be torn and will prevent the wire from wearing through said tag.

As a modification of my improved tag or check I contemplate making one side or surface thereof continuous, the slot *a* extending only part way through the same, as shown in Fig. 5. With this construction it is obvious that the tag may be attached in the same manner as where the slot *a* extends entirely through the tag or check.

My invention therefore contemplates a slot 10 which extends partly or entirely through the tag.

I claim—

1. A tag or check comprising separate layers of suitable material secured together, 15 a slot in said tag, a wire inserted between the layers of said tag, said wire comprising a section which extends longitudinally of said tag and a needle formed continuous with each other, said needle extending longitudinally 20 of the slot formed in said tag, the point of said needle being normally disposed inside of the lateral surfaces of said tag or check, substantially as described.

2. A tag or check comprising separate 25 layers of suitable material secured together, a slot in said tag, a wire inserted between the layers of said tag, said wire comprising a section which extends longitudinally of said tag, a section which extends transversely of said 30 tag and a needle all continuous with each other, said needle extending longitudinally of the slot formed in said tag, the point of said needle being disposed inside of the lateral surfaces of said tag or check, substantially as described.

3. A tag or check comprising separate 35 layers of suitable material secured together, a slot in said tag, a wire inserted between the layers of said tag, said wire comprising a section which extends longitudinally practically 40

the entire length of said tag or check, a section which extends transversely of said tag and a needle all continuous with each other, said needle extending longitudinally of the slot formed in said tag, the point of said needle 45 being disposed normally inside of the lateral surfaces of said tag or check, substantially as described.

4. A tag or check comprising separate layers of suitable material secured together, 50 a slot in said tag, a wire inserted between the layers of said tag, said wire comprising a section which extends longitudinally of said tag or check and a needle formed continuous with each other, said needle extending longitudinally 55 of the slot in said tag and being disposed inside of the lateral surfaces of said tag or check, and said tag or check being relatively thick adjacent to the point of said needle, substantially as described.

5. A tag or check comprising separate layers secured together, a slot in said tag, a wire inserted between the layers forming said tag, said wire comprising a section which extends longitudinally of said tag and a needle formed 65 continuous with each other, said needle extending longitudinally of the slot formed in said tag or check and pieces of relatively strong, tough fabric, as muslin or cheese-cloth, secured between the layers of the tag 70 or check on opposite sides of the wire, substantially as described.

In testimony that I claim the foregoing as my invention I affix my signature, in presence of two subscribing witnesses, this 18th day of July, A. D. 1901.

CHARLES B. FAIRCHILD.
